UNITED STATES PATENT OFFICE

JAMES A. HENRY AND JOHN H. YANCEY, OF STURGIS, MICHIGAN

REGISTER

Application filed October 28, 1931. Serial No. 571,708.

The main object of our invention is to provide an autographic register that is simple and economical in construction, inexpensive in manufacture, and convenient and efficient in operation.

Another object of our invention is to provide improved means for facilitating the feed or adjustment of the record strip or strips so as to correctly position them for the entry of a record thereon.

Objects relating to details and economies of our invention will appear from the description to follow. The invention is defined and pointed out in the claims.

15 A structure which is a preferred embodiment of our invention is illustrated in the accompanying drawings, in which:

Fig. 1 is a perspective view of an autographic register embodying the features of 20 our invention.

Fig. 2 is an enlarged view in side elevation, parts being broken away and shown in longitudinal vertical section.

Fig. 3 is a top plan view of the register with 25 the cover removed, parts of the writing table being broken away.

Fig. 4 is an enlarged fragmentary vertical section of parts shown in Fig. 2.

Fig. 5 is an enlarged fragmentary section 30 taken on line 5—5 of Fig. 3, showing details of the carbon paper feed.

Fig. 6 is an enlarged view in side elevation of a modification, parts being broken away and shown in vertical longitudinal section, 35 taken on line 6—6 of Fig. 7.

Fig. 7 is a top plan view, parts being broken away and shown in longitudinal section on line 7—7 of Fig. 6.

Referring to Figs. 1 to 5, inclusive, of the 40 drawings, there is illustrated a manifolding autographic register constructed in accordance with our invention which comprises a removable cover 1 which is adapted to fit over the box 2, the top of which is open. The box 2 constitutes a compartment for storing the record strip or strips 3 which are adapted to be fed and positioned over the writing table 4 mounted within the cover or casing 1. The writing table 4 is spaced slightly below 45 the top 5 of the cover which has a rectangular

opening 6 for the entry of a record on the record strip or strips 3, as illustrated by Fig. 2. The inner end 7 of the writing table 4 is preferably curved downwardly as illustrated. The cover has an opening 8 for the passage 55 of the strips.

The strips 3 are weakened on transverse lines 9 against bending resistance so that a distinct checking impulse is imparted to the advancing strip when the weakened lines 9 60 reach the apex of the pivoted transverse strip positioning detent 10 which is mounted within the box at the rear of the writing table 4. The detent 10 is pivoted to the walls 11 of box 2 at 12 and is provided with a rearwardly 65 extending arm 13, the rocking movement of which is limited by stops 14 and 15. The upper stop 14 determines the initial position of detent 10 which is urged to such position by leaf spring 16 carried by bracket 17. The bracket 17 is fixed to the wall 11 at 18.

As illustrated by Figs. 2 and 4, the strips 3 are advanced until the weakened lines 9 engage the detent 10 whereupon a distinct 70 increase in resilience results, so that the operator is made aware that the strips are in proper position for the making of entries thereon. At this point the old record may be torn off at 19.

The checking action of detent 10 is materially assisted by the vertically floating roller 20 which is adapted to ride on the strips 3 above the apex of detent 10. When the strips 3 are advanced, detent 10 is rocked against the force of spring 16 and the weighted 75 roller 20 is elevated so as to release the weakened lines 9 of the strips 3 from the detent 10. However, when the succeeding weakened lines 9 are presented at the apex of detent 10, the weighted roller 20 coacts with the detent 80 to increase the checking action of the latter on the strips.

As illustrated by Figs. 3 and 5, strips of 85 transfer paper 21 are arranged between the record strips 3 over the writing table 4 so that records made on the top strip will be transferred to the lower strips. The transfer strips 21 are supplied from the supply roll 22 which is carried by the spool or spindle 100 90

In the modification illustrated by Figs. 6 and 7 of the drawings, the pivoted detent 10' is of slightly different construction and consists of a plate having flanged ends which are pivoted to the walls 7' at 12'. The leaf spring 16' carried by stationary bracket 17' urges the detent 10' upwardly or in its initial position. The weighted roller 20' rests on the strips 3' immediately above the apex of detent 10', as illustrated by Fig. 6. Stop 14' limits the rocking movement of detent 10' under the influence of leaf spring 16'. The operation of the detent 10' and 20' in checking the advance of the strips 3' is similar to that described above in connection with Figs. 1 to 5, inclusive. In the embodiment illustrated by Figs. 6 and 7, also, the box 2' is open ended and is provided with a sliding removable bottom 24 and side guide plates 25 for facilitating the adjustment of the record strips 3'.

It is obvious that various changes and modifications may be made in the details of construction and design of the above specifically described embodiments of our invention without departing from the spirit thereof, such changes and modifications being restricted only by the scope of the following claims.

Having thus described our invention what we claim as new and desire to secure by Letters Patent is:

1. In a register of the class described, the combination with a casing having a compartment for storing a record strip, a writing table over which said strip may be positioned for entry of a record thereon, a pivoted transverse strip positioning detent over which the strip passes when drawn forwardly to said writing table, said strip being weakened on transverse lines against bending resistance and engaging said detent at said weakened lines to increase the resistance to the strip so as to facilitate the positioning of the strip upon said writing table, a vertically floating weighting roller coacting with said pivoted detent, stops limiting the rocking movement of said detent, and leaf spring means coacting with said pivoted detent to urge it into engagement with one of said stops whereby to resiliently hold it in an initial position such that when the strip is moved forward said detent is rocked against the force of said means to facilitate releasing said strip at said weakened lines.

2. In a register of the character described, the combination with a casing having a compartment for storing a record strip, a writing table over which said strip may be positioned for entry of a record thereon, a pivoted transverse strip positioning detent over which the strip passes when drawn forwardly to said writing table, said strip being weakened on transverse lines against bending resistance and engaging said detent at said

weakened lines to increase the resistance to the strip, so as to facilitate the positioning of the strip upon said writing table, and a floating weighting roller coacting with said pivoted detent, stops limiting the rocking movement of said detent, and spring means coacting with said pivoted detent to urge it into engagement with one of said stops. 70

3. In a register of the character described, the combination with a casing having a compartment for storing a record strip, a writing table over which said strip may be positioned for entry of a record thereon, a pivoted transverse strip positioning detent over which the strip passes when drawn forwardly to said writing table, said strip being weakened on transverse lines against bending resistance and engaging said detent at said weakened lines to increase the resistance to the strip feed so as to facilitate positioning of the strip upon said writing table, stops limiting the rocking movement of said detent, and spring means coacting with said pivoted detent to urge it into engagement with one of said stops. 80

4. In a register of the character described, the combination with a casing having a compartment for storing a record strip, a writing table over which said strip may be positioned for entry of a record thereon, a pivoted transverse strip positioning detent over which the strip passes when drawn forwardly to said writing table, said strip being weakened on transverse lines against bending resistance and engaging said detent at said weakened lines to increase the resistance to the strip feed so as to facilitate positioning of the strip upon said writing table, and spring means coacting with said pivoted detent to urge it into engagement with one of said stops. 90

5. In a device of the class described, the combination with a casing having a compartment for the storing of a record strip weakened on transverse lines against bending resistance, a writing table at the top of said casing, a pivoted strip positioning detent disposed at the rear of said table and over which the strip is drawn in passing to the table, stops for limiting the pivotal movement of said detent, a spring acting to normally urge said detent downwardly and against one of said stops, and a floating weight adapted to ride on the strip above said detent. 110

6. In a device of the class described, the combination with a casing having a compartment for the storing of a record strip weakened on transverse lines against bending resistance, a writing table at the top of said casing, a pivoted strip positioning detent disposed at the rear of said table and over which the strip is drawn in passing to the table, stops for limiting the pivotal movement of said detent, and a spring acting to normally 120

urge said detent downwardly and against one of said stops.

7. In a device of the class described, the combination with a casing having a compartment for the storing of a record strip weakened on transverse lines against bending resistance, a writing table at the top of said casing, a pivoted strip positioning detent disposed at the rear of said table and over which the strip is drawn in positioning on the table, and a floating weight adapted to ride on the strip above said detent.

8. In a device of the class described, the combination with a casing having a compartment for the storing of a record strip weakened on transverse lines against bending resistance, a writing table at the top of said casing, and a pivoted strip positioning detent disposed at the rear of said table and over which the strip is drawn in positioning on the table.

9. In a device of the class described, the combination with a casing having a compartment for the storing of a record strip weakened on transverse lines against bending resistance, a writing table at the top of said casing, a strip positioning detent disposed at the rear of said table and over which the strip is drawn, and a floating roller adapted to ride on the strip above said detent.

In witness whereof we have hereunto set our hands.

JAMES A. HENRY.
JOHN H. YANCEY.
